(57) **CLAIM**

We claim the ornamental design for an “area light,” as shown and described.

DESCRIPTION

FIG. 1 is a top perspective view of an area light showing my new design, including an enlarged callout for ease of illustration.

FIG. 2 is front end view of the area light shown in FIG. 1, showing an enlarged callout for ease of illustration detailing edges of the area light; and,

FIG. 3 is a top plan view of the area light shown in FIG. 1, showing an enlarged callout for ease of illustration detailing fins of the area light.

The broken lines are only for illustrative purposes to show visible environmental structure and form no part of the claimed invention. The long-dash short-dash lines of the callout boundaries form no part of the claimed invention.

1 Claim, 2 Drawing Sheets
